No. 888,272.

PATENTED MAY 19, 1908.

M. C. THAYER.

APPARATUS FOR ATTACHING STAY CORDS TO BUTTONHOLE PIECES.

APPLICATION FILED MAR. 4, 1908.

UNITED STATES PATENT OFFICE.

MAYNARD C. THAYER, OF MANCHESTER, NEW HAMPSHIRE, ASSIGNOR TO THE REECE
BUTTON-HOLE MACHINE COMPANY, OF BOSTON, MASSACHUSETTS, A CORPORATION
OF MAINE.

APPARATUS FOR ATTACHING STAY-CORDS TO BUTTONHOLE-PIECES.

No. 888,272.

Specification of Letters Patent.

Patented May 19, 1908.

Application filed March 4, 1908. Serial No. 419,130.

To all whom it may concern:

Be it known that I, MAYNARD C. THAYER, a citizen of the United States, and resident of Manchester, county of Hillsboro, State of New Hampshire, have invented an Improvement in Apparatus for Attaching Stay-Cords to Buttonhole-Pieces, of which the following description, in connection with the accompanying drawing, is a specification, like letters on the drawing representing like parts.

This invention has for its object the production of apparatus for attaching stay-cords to button-hole pieces by means of a "blind-stitch", whereby the cord and the stitching which secures it in place will be invisible at the opposite side of the work. The stay-cord above referred to is attached to the under-side of a button-hole piece adjacent the "eye" end of a series of button-holes formed therein, to strengthen the button-holes when subjected to strains at the eye, and heretofore such stay-cord has been attached and held in place by through and through stitching, which shows at the face of the work.

In my present invention I have provided a fixed guide through which the stay-cord is delivered to the stitch-forming mechanism, at the under-side of the work, said guide being located adjacent means which bend the work just before the needle penetrates the same, the needle point entering and emerging from the same side of the work, producing a blind-stitch.

I have herein shown my invention applied to a sewing-machine having work-bending means and stitch-forming mechanism substantially as shown in United States Patent No. 404863 granted to John Reece July 11, 1889.

Figure 1 of the drawing is a top plan view of a sufficient portion of a sewing-machine such as is illustrated in said patent, with my invention applied thereto, the cover-plate being removed and the overhanging arm omitted; Fig. 2 is an end view of the machine, with the casing broken out and some of the parts in section; Fig. 3 is an under-side view of a button-hole piece with the stay-cord applied thereto by blind-stitching.

The bed-plate A, main shaft A², the vertically reciprocating bender A⁹, Fig. 2, the groove a in the throat-plate a', held in place

on the bed-plate by screws a², the presser-foot B', the reciprocating eye-pointed needle a⁶ secured to the horizontal needle-bar a⁷ having its bearings in a yoke a⁸ mounted on pivots a⁹, a¹⁰, Fig. 2, the link b pivotally connecting the needle-bar with a disk b² on the main shaft A², the needle-guide b³ rising and falling in a slot in the bottom of the groove a of the throat-plate by the co-operation of the cam-shaped periphery of the disk b² with a spring 5 acting upon a spring-arm 8 extended under the needle-guide, and the shuttle c, see dotted lines Fig. 1, to catch the loop of needle-thread, may be and are all substantially as in the above-mentioned patent and operate as therein set forth. The feed-bar d² is of the four-motion type, engaging the under-side of the work, and being actuated in the usual manner from cams, not shown, on the shaft A².

The work is fed in the direction of the longitudinal reciprocation of the needle, as in the patent referred to, and the descent of the bender A⁹ acts upon the work to form a bend therein in the groove a of the throat-plate, the needle entering the bent work first at one and then at the other side of the stay-cord, and to effect this lateral vibration of the needle a link a⁴ is connected at one end to the yoke a⁸, and at its other end the link cooperates with a block 21 which enters a groove in a pivoted arm e, said arm having a suitable stud which cooperates with the grooves of a double-grooved switch-cam e², Fig. 1, all as in the Reece patent. By the specified means the needle point enters the work on alternate thrusts, at opposite sides of the cord which is delivered as will be described, so that the said cord is fastened in place by blind stitching.

I will now describe the guide for directing the stay-cord so that it can be laid along the under face of the work and delivered at a point close to the work-bending means, so that the needle on alternate thrusts will penetrate the bent work at opposite sides of the cord, in order to attach the same by blind-stitching to the work.

Upon the cover plate 30 of the machine, held in place by a screw 32, Fig. 1, in front of the bender A⁹ I mount a flat plate 31, holding the same fixedly yet adjustably in place by screws 32^x, Fig. 1, the end of the plate

near the groove *a* being beveled or converging to substantially a point, at 33.

Upon the pointed end of the plate I rigidly mount a tubular guide 34, having its delivery end preferably slightly rounded off or beveled, as at 35, Fig. 2, the guide being located parallel to the reciprocating path of the needle, and midway between the extremes of its lateral vibrating movements. 10 The stay-cord 36 is led through the guide and is delivered at the under side of the work *W*, and when the bend is formed in the latter the cord is bent with it so that as the stitch-forming mechanism operates the cross- 15 stitches 37, Fig. 3, will cross the cord from side to side, securing the cord to the work by blind stitches, invisible from the opposite face of the work. The guide, by delivering the cord at the bending point and with 20 proper relation to the movements of the needle, enables the operator to control the movement of the work as it is fed in the direction of the length of the needle, so that the stay-cord will always be laid at the 25 proper point to be stitched to the work. Back of the guide 34 and in alinement therewith I mount a tubular eye 38, through which the cord is threaded before it enters the guide, and a grooved sheave 39 is rotatably mounted on the plate 31 substantially tangential to the line of feed of the cord, to direct the latter from the side eye 40 and to the eye 38. The guide and eye 38 could be 30 made as a continuous tube, but it is easier 35 to thread up by making the two parts separate, as I have herein shown.

In Fig. 3 I have shown a button-hole piece with a series of button-holes *w*, and the stay cord 36 is shown as secured to the piece 40 by the blind stitching 37 close to the eye-

ends of the button-holes, to strengthen them at such points when strain is applied thereto.

It will be understood that the under side of the button-hole piece is shown in Fig. 3, the stay-cord and stitching holding it in place being invisible from the face of the work.

Having fully described my invention, what I claim as new and desire to secure by Letters Patent is:—

1. In a sewing-machine, stitch-forming mechanism, including a longitudinally-reciprocating needle laterally vibrated on alternate thrusts, means to intermittently engage and form a transverse bend in the work prior to each thrust of the needle, an elongated cord-guide parallel to the longitudinal path of movement of the needle and having its delivery end adjacent the bending means, to deliver a stay-cord thereto and to 55 the stitch-forming mechanism, at the under-side of the work, and a directing eye for the cord in front of and alined with the guide.

2. A stay-cord guide for button-hole finishing machines, comprising a plate adapted 65 to be fixedly secured in place, a tubular guide rigidly mounted thereon, through which the stay-cord passes and from which it is delivered, and a grooved sheave rotatably mounted on the plate with its periphery tangential to the tubular guide, the cord drawing around the sheave as it passes to the guide.

In testimony whereof, I have signed my name to this specification, in the presence of 75 two subscribing witnesses.

MAYNARD C. THAYER.

Witnesses:

LIZZIE HARVEY,

CHARLES D. BARNARD.
